(57) **CLAIM**

The ornamental design for a wheel chock, as shown.

DESCRIPTION

FIG. 1 is a handle-end, right side isometric view of a wheel chock showing our new design;

FIG. 2 is a handle-end, bottom isometric view thereof;

FIG. 3 is a right side view thereof;

FIG. 4 is a top view thereof;

FIG. 5 is a left side view thereof;

FIG. 6 is a bottom view thereof;

FIG. 7 is an end view thereof, as viewed along the section lines 7—7 of FIG. 4; and,

FIG. 8 is an end view thereof, as viewed along the section lines 8—8 of FIG. 6.

FIGS. 3—6 are shown on an enlarged scale as compared with FIGS. 1 and 2.
